UNITED STATES PATENT OFFICE.

ANTON SCHRADER, OF CASTROP, POST RAUXEL, GERMANY, ASSIGNOR OF ONE-HALF
TO OTTO LAMBERT, OF CASTROP, GERMANY.

DOOR-KEY.

1,082,560.

Specification of Letters Patent.

Patented Dec. 30, 1913.

Application filed June 16, 1913. Serial No. 774,050.

To all whom it may concern:

Be it known that I, ANTON SCHRADER, a subject of the Emperor of Germany, residing at Castrop, Post Rauxel, Westphalia, Germany, have invented certain Improvements in Door-Keys, of which the following is a specification.

The present invention relates to a door key and consists in the provision of a handle 10 in the form of a clock-work-operated bell, and of a hollow stem holding a spring-actuated rod which can be depressed for releasing the clock-work and sounding the bell. The rod is fitted with a push button which 15 projects through one side of the lock when the key is introduced from the other.

In the accompanying drawings the invention is illustrated, Figure 1 representing a 20 sectional view of the device, and Fig. 2, an elevation of the same at right angles to Fig. 1.

The key stem *a* is made hollow for the reception of a rod *b* adapted for longitudinal displacement. The handle of the key is 25 composed of a bell *f* which is adapted to be rung by means of a clock-work in known manner. A head *d*, secured to the bell end of the rod *b*, is pressed by a spring *e* which is arranged in the bell and which is so connected to the clock-work as to release the 30 same for sounding the bell when the rod *b* is depressed. For depressing the rod *b* a push button *c*, having the same diameter as the stem *a*, is secured to the outer end of the 35 rod, the latter being prolonged beyond the

end of the stem sufficiently for allowing a depression.

When the key is placed in the lock, the push-button *c* projects at the opposite side *a* of the same so that a person outside the door 40 can depress the button for ringing the bell.

The bell *f* is so connected to the stem *a* that the center of gravity is out of register with the axis of the stem. It has thus a tendency to hold the key in a certain position. The bit *g* of the key is so arranged as to be out of register with the key-hole when the key occupies the position determined by the bell. Owing to this arrangement, which is known *per se*, a dislocation of the key by 50 means of the push button *c*, is prevented.

I claim:—

A door key having a hollow stem, a handle in the form of a clock-work-operated bell connected to said stem, a spring-actuated rod arranged in the hollow stem so that it can be displaced longitudinally for releasing the clock-work and ringing the bell, and a push-button connected to the outer end of the rod, said push button being arranged so that it can be depressed, from one side of the lock, for ringing the bell, when the key is inserted into the lock from the other side, the bell being connected to the stem so as to tend by gravity to hold the 60 key-bit out of register with the key-hole.

ANTON SCHRADER.
